LOOSE SHEET HOLDER

Joseph Eifel, Chicago, Ill.

Application December 17, 1921, Serial No. 523,086

14 Claims. (Cl. 129—13)

This invention relates broadly to engaging means and more particularly relates to means for engaging and locking one or a plurality of sheets in predetermined position.

5 Among the more important objects which characterize this invention are: the arrangement whereby a plurality of sections are assembled to form a base having variable dimensions, and means for locking the base in adjusted 10 positions, together with engaging members on the base for engagement with and retention of one or more sheets; the embodiment wherein the base may be adjusted to various sizes and locked; wherein is embodied a lever mechanism for connecting the several relatively adjustable sections forming the base; the mechanical organization whereby the engaging members may be angularly displaced as a unit relative to the base and locked; the relatively movable elements forming 15 20 the engaging elements whereby a sheet is locked by the relative movement of these elements in one direction, and released by relative movement of the elements in another direction, in other words, the manner of securing the sheets 25 by changing the contour of the sheet-engaging elements; the opposed group arrangement of the sheet-engaging elements and means for relatively shifting the said elements, together with the means for connecting the sheet-engaging elements of the two or more groups whereby simultaneous locking and releasing movement of the 30 same is attained; the provision of sheet-engaging elements which are variable in length as desired; the locking arrangement for retaining the sheet 35 engaging members in angularly adjusted positions; and the general compactness, ruggedness and utility of the device.

In the attainment of the objects and such other objects and advantages as may hereinafter 40 appear, I have provided a structural embodiment which indicates one mode of carrying out the aims of this invention which structure is illustrated in the accompanying drawings, in which—

Figure 1 is a plan view, with parts in section, 45 of the device embodying the improvements of this invention;

Figure 2 is a transverse sectional view taken on the plane of line 2—2 of Figure 1, looking in the direction indicated by the arrows;

50 Figure 3 is a longitudinal sectional view taken on the plane of line 3—3 of Figure 1, looking in the direction indicated by the arrows;

Figure 4 is a longitudinal section taken on line 4—4 of Figure 1 looking in the direction of the 55 arrows;

Figure 5 is a sectional view taken on line 5—5 of Figure 2, looking in the direction of the arrows;

Figure 6 is a view similar to Figure 4 of a modification;

Figure 7 is a fragmentary sectional view of a detail of a modification;

Figure 8 is an end elevation illustrating a modified form of lock for the sheet-holding members;

Figures 9 and 10 are fragmentary plan and end views, respectively, of a further modified form of the invention.

Figure 11 is a section taken on line 11—11 of Figure 9, looking in the direction indicated by the arrows;

Figure 12 is a section taken on line 12—12 of Figure 10, looking in the direction of the arrows;

Figures 13 and 14 are elevational and sectional views, respectively, of the sheet-engaging pins, the latter view taken on line 14—14 of Figure 1;

Figure 15 is an end elevation of one of the locks for holding the pin-carrying elements in adjusted position;

Figure 16 is a detail view of a modified form of lock for the base sections;

Figure 17 is a fragmentary plan view of an alternative form of the invention, parts being shown in section, taken on the line 17—17 of Figure 18, looking in the direction indicated by the arrows;

Figure 18 is a sectional view taken on the line 18—18 of Figure 17, looking in the direction indicated by the arrows;

Figure 19 is a sectional view taken on the line 19—19 of Figure 17, looking in the direction indicated by the arrows;

Figure 20 is a sectional view of a still further alternative form of the invention.

Referring more particularly to the drawings which illustrate certain preferred and modified embodiments of this invention, and with special reference to Figures 1 to 5, inclusive, it will be observed that I have provided a binder for loose sheets which includes generally a base 10, and side or sheet-engaging member carrying sections 11 and 12. These sheet-engaging, member-carrying sections are substantially identical in construction, with few exceptions, which will appear hereinafter, and therefore a description of but one, together with the exceptions, will suffice.

As will be seen best in Figures 1 to 3, inclusive, the base 10 comprises an intermediate portion which includes a bottom plate 13, said plate extending longitudinally of the device and having 110

its free ends upturned at 14—14 and engaged over a cover plate 15, thus affording a longitudinal chamber 16 for a purpose which will presently appear.

The base 10 further includes the longitudinal supporting plates 17 and 18 which have their adjacent margins receivable within the chamber 16, the outer portion of the plates 17 and 18 being secured to the hinge leaves 19 and 20, which latter are provided with hinge barrels 21 and 22, respectively, which engage the hinge pins 23 and 24, respectively, carried by the side sections 11 and 12. Machine screws 25—25 serve the purpose of fixedly connecting the plates 17 and 18 to the hinge leaves 19 and 20.

The bottom plate 13 and the top plate 15 forming the chamber 16 provide what might be termed the intermediate portion 10 of the base, and this intermediate portion is so related to the sections composed of the parts 11, 12, 19, 20, 17 and 18 that the latter are movable in opposite directions toward and away from each other relatively to the intermediate section, thus affording a base of variable dimensions.

In order to afford the adjustment referred to above and to lock the intermediate and outer end sections of the base in various positions as desired, and in order to insure the even relative displacement of these elements, I provide a lever arrangement which in its entirety takes the form of a lazy-tongs and is exemplified in Figure 1 by the links 26 and 27 articulated on a pin 28 which extends transversely through the bottom and top plates 13 and 15; links 29 and 30 articulate with the links 26 and 27 at their respective intermediate portions on pins 31—31; the latter-mentioned links being articulated with the hinge plates 19 and 20 on the pins 32—32. The other ends of the links 29 and 30 are articulated on a pin 33 which extends through the plates 13 and 15 and is slidably in aligned slots 34 in said plates. Similarly, the ends of the links 26 and 27, remote from the pivot 28, are provided with pins 35—35 which lie each in slots 36—36 provided in the hinge plates 19 and 20.

In order to provide for compactness and to allow for the relative positions of the links 26, 27, 29 and 30, the hinge leaves 19 and 20 are made in two sections each as best seen in Figure 1.

It will be observed that, for convenience in construction of the links and their assembly, the link 29, at its end adjacent to the bottom of Figure 1, overlies the extending portion 19, and also overlies the link 26 which latter, at the upper left-hand side of Figure 1, underlies the horizontal portion of the adjacent hinge leaf. It will also be observed that the link 27 overlies the adjacent hinge leaf at the upper right-hand side of Figure 1 and that the link 30 underlies the adjacent hinge leaf at the lower right-hand side of Figure 1. However, it will further be observed that as the links 27 and 29 overlie the diagonal opposite portions of the hinge leaves and, as well, overlie the links 30 and 26, respectively, and as these latter links underlie the portions of the hinge leaves to which they are connected, these latter portions of the hinge leaves must be offset upwardly, as indicated at 37 and 38, to receive the adjacent portions of their respective links as the binder is expanded or contracted.

From the foregoing it will be seen that the link arrangement described will permit of the portions of the base being relatively slidably adjusted to attain various dimensions, the lower pivots 28 and

32 being fixed and the upper pivots 33 and 35 being slidable as viewed in Figure 1. The ends of the links 27 and 29 overlie the adjacent portion of their respective leaves and thus the planes in which these leaves lie are proper to insure smooth operation of links.

In order to lock the sections of the base in the different dimensions which the same may assume when adjusted, one of the links, in the present instance 26, carries a toothed lug 39 which is adapted to engage with a complementally toothed arm 40 carried at one end of a slidably mounted plate 41, which plate is secured to and slidable upon the underface of the hinge leaf 19 by means of pins 43 and 32. It will be understood that the arm 40 lies in the plane of movement of the lug 39, the free end of the plate 41 being bent upwardly through a slot 44 in the hinge leaf 19 to form a finger-engaging member 45 whereby the lock may be manipulated. A spring 46 is secured at 47 to the upper face of the hinge leaf 19 and bears against the finger piece 45 so as to always tend to maintain the teeth of the arm 40 in engagement with those of the lug 39.

The sections 11 and 12 serve to carry the sheet-engaging fingers and these sections 11 and 12 are angularly adjustable relatively to the base on the hinge pins 23 and 24 and contain mechanism for manipulating the sheet-engaging fingers whereby to lock or release the sheets held in the binder. The sections 11 and 12 preferably comprise the longitudinal housings 48 and 49 and as the contents of these housings are substantially identical with exceptions pointed out hereinafter, I will describe the contents of the housing 48 only. It will be observed that the housing is rectangular in cross-section although this may be varied as found desirable, and that arranged within the housing, as best shown in Figures 1, 4 and 5, are a plurality of brackets 50, which brackets are secured in desired number and location within the housing.

The brackets 50 carry each a pin 51 (see Figs. 1 and 4) which is termed the stationary element of the sheet-engaging members to be described presently, and these pins project through the inner wall 52 of the housing 48, which wall is secured to the top and bottom walls of the housing in any desired manner, and carry the enlarged portions 53—53 which are intended to engage the sheets.

Complemental pins 54 and 54' are arranged above and adjacent to the pins 51—51 and project through suitable slots 55 (see Fig. 3) formed in the wall 52 of the housing, and these pins may be termed the movable elements of the sheet-engaging members. These pins 54 and 54' are carried by reciprocable bars 56 and 57, respectively, which bars are slidably mounted for movement in opposite directions within the housing 48. The pins 54 are carried by the bar 56, and the pins 54' by the bar 57, so that displacement of the pins will be with their respective bars. It will thus be seen that the pins 51 and 54 form the elements of the units which make up each one of the sheet-engaging members.

In order to reciprocate the bars 56 and 57 in opposite directions, a disk 61 is mounted for rotation within the housing upon the endmost left-hand bracket as viewed in Figures 1, 4 and 5. This disk is provided with a squared stud 62 which projects through a suitable opening 63 in the wall 52 to receive a wing nut 64 for imparting rotation to the disk manually. A pair of pins 65 are mounted at diametrically opposite points on the disk 61 and project rearwardly therefrom and lie

145

150

within transverse slots 66 formed in enlarged portions 67—67 on the bars 56 and 57. It will be understood that when the disk is rotated through the medium of the wing nut, this motion, through the medium of the pin and slot described, will impart rectilinear motion in opposite direction to the bars 56 and 57. The disk mechanism is, of course, duplicated at 61a on the opposite side of the binder.

10 The covers of the binder of this invention are shown at 68 and 69, and are hinged on the sections 11 and 12 this being accomplished by means of the housings 48 and 49, which housings preferably comprise the walls 70 and 71 formed with hinge barrels 72, 72, which latter barrels encircle the hinge pins 23 and 24 and are provided with extending lips 73 which engage the under portions of the brackets 50—50 and walls 52, the upper portions of the walls 70 and 71 having hinge barrels 20 74 which encircle the hinge pins 75 of the covers 68 and 69. Thus the brackets 50—50 and walls are supported by the members 70 and 71 to make up the complete housings and said members 70 and 71 are hingedly connected with the leaves 19 25 and 20 through the pins 23 and 24 and also hingedly connected with the covers 68 and 69 through the respective hinge pins provided therefor.

It will be observed that two types of finger members for engagement with the sheets have 30 been illustrated but I will describe but one form at this time, namely, that form shown in Figure 1.

As will be seen from Figure 1, the pins 54, 54' project from the housings 48 and 49 and are split 35 to retain the sleeve sections 51', these sections being frictionally retained in position on the pins 54, 54' at any desired point so as to provide for variable length of the finger. The sleeves 51' in one form are in turn provided with reduced slotted 40 portions 76, which portions are adapted to receive each a cap 77 of substantially the same diameter as that of the sleeve portion 51'.

It will be understood that the cap members 77 immediately opposite the pins of each set will 45 abut when the binder is closed so as to hold the sheets in position.

A modified form of the construction just described is illustrated in Figures 1, 13 and 14, wherein the sleeve section 51' has a solid end 50 portion 51b which is provided with a plurality of longitudinally arranged external grooves 55' which are adapted to receive complementally formed tongues 56' on the cap member 77'.

Where it is desired to connect the opposite 55 sets of sheet-engaging elements or pins simultaneously, I provide structures for this purpose illustrated in Figures 17 to 20, both inclusive, which will presently be described.

As shown in dotted line in Figure 3, the paper 60 sheet is designated 85 and this sheet is provided with a pair of groups of notches 86 in one edge thereof, the notches having offset recesses 87 in the inner ends thereof. As will be observed from Figure 3, the offset portions of the notches of 65 the respective pairs referred to are oppositely disposed to receive the pin sleeves 51' of the two groups as these pins are displaced for locking in opposite directions.

When the pins are in the position shown in 70 Figures 3 and 4, their sleeves 51' will engage in the respective recesses 87 of the pairs of groups of notches in the sheet and retain the latter against displacement. Upon rotation of the disk and the consequent bringing of the pins 54 and 75 54' into vertical alignment with the pins 51, the

sheet may be removed. It will thus be seen that the paper is retained by changing the contour or the relative angular position of the fingers which engage the sheets and that each group of sheet-engaging fingers is simultaneously operated to perform the desired function.

Another manner of accomplishing the result just referred to is shown in Figures 6 and 7. In this instance the bars 56 and 57 both extend the entire length of the section 11, and carry each an entire series of pins 88 and 89, respectively, said pins lying relatively close together and adapted for movement in opposite directions to engage or disengage in complementary recesses formed in the sheet. In this instance the sheet is provided with a plurality of notches 90 along one edge thereof, said notches having oppositely disposed lateral recesses 91 and 92 so aligned as to be engaged by the pins 88 and 89, respectively, when the latter are displaced to offset or angular position to each other as shown in Figure 6. When the pins are in alignment, as shown in Figure 7, the sheet may be removed.

It will be understood that while sheets may be removed from the pin members by aligning them, yet in some circumstances it is desired to transfer sheets from one set of pins to the other without removing the entire group of sheets from the binder and, in order to accomplish this end, the sheet-engaging elements are arranged for 100 angular adjustment relative to the base.

Where the opposed sets of pins are to be operated in unison, then the form of the invention shown in Figures 17 to 20 may be employed, it being understood that in that event the operating mechanism of the pins, represented by the elements 61, 64, 65, etc., will be omitted from one or the other of the opposed hinge leaves.

As a means for maintaining the housings 48 and 49 in angular adjustment relative to the base, the hinge leaves 19 and 20 are each provided with an angularly adjustable locking device, and, as these devices are identical, but one will be described. This locking arrangement is best shown in Figure 15, wherein a segmental plate 93 is carried by the hinge leaf 19, and preferably formed integrally therewith, this plate 93 lying in a plane at right-angles to the leaf 19 adjacent to the end of the housing 48. The latter is provided with a segmental plate 94 formed integrally 115 with the wall 70 and lying in a plane parallel with and in surface contact with the segmental plate 93. The latter is provided with an arcuate slot 95 described about the hinge pin 23 as a center, and a set screw 96 extends through said slot and into the segmental plate 94 for retaining the plates 93 and 94 in position for relative angular adjustment. A spring washer 97 is interposed between the head of the screw and the plate 93.

As an alternative manner of manipulating the bars 56 and 57, I have provided a rack and pinion arrangement shown in Figure 11. Here it will be observed that a pinion 98 is arranged in the place of the disk 61, this pinion being provided with a polygonal stud 99 to which a wing nut may be attached. The pinion engages with rack teeth 98' and 99' formed on the bars 56 and 57, respectively.

In Figures 9 and 10 the pinion and rack engagement, just described, is embodied in a modified form of the invention wherein locking and releasing movement of the sheet-engaging members is obtained as well as the variable dimensioning of the base and its locking, the arrangement 145

80

85

100

105

110

115

120

125

130

135

140

145

150

here permitting angular adjustment of the side sections. It will be understood that in this form of the invention the combined features of simultaneous operation of the sheet-engaging elements 15 may be accomplished, and that angular adjustment of the sheet-engaging elements for the transfer of sheets from one set to the other is facilitated.

This arrangement includes the housings 48 and 49 and their associated pin-operating mechanisms, together with the rack and pinion arrangement. In this case, both of the housings contain the rack and pinion arrangement and shafts 100 project from the housings in opposite directions 15 toward the center of the base. The shafts 100 carry universal joints 101 which connect to oppositely disposed straps 102, the free ends of which straps are received in sleeve members 103, of which there are a pair arranged in the parallel 20 rectangular bores 104 provided in spaced parallel relation in the block 105. The sleeves 103 are each provided with a slot 106, which slots terminate short of the ends of the sleeve members and are adapted to receive each a pin 107 carried by 25 the straps 102, thus permitting relative movement of the sleeves and their straps as well as confining this relative movement within certain limits. The sleeves may be locked against movement at any desired location in the block 105 by 30 means of winged set screws 108, each one of these set screws impinging on one of the sleeves. The remaining parts of the device shown in Figures 9 and 10 are identical with that form of the invention shown in Figures 1 and 2.

In the operation of this form of the invention, rotation of the block 105 imparts rotation to the pinions 98 and thus simultaneously operates the sheet-engaging elements carried by the binder. Where it is desired to angularly adjust the sheet-engaging members, the same are swung on their respective hinges and universal joints 101 permit of this movement, it being obvious that the block 105 floats between the side sections or housings. Where it is desired to extend the base or contract 45 the same and thus vary its dimensions, the wing screws 108 may be released from the sleeve member 103 so as to permit such adjustment as is required. The universal joints permit manipulation of the sheet-engaging elements regardless of 50 the angle of disposition of the same relative to the base.

Referring now to Figure 8, a further modified form of the invention is shown, this form illustrating particularly a modification of the means 55 for manipulating the disk 61, and also another form of lock for the base sections. In this form of the invention, the disk 61 is provided with an annular flange 62 which is adapted to engage the inner surface of the wall 52, the disk carrying the pins 65 previously described. A stud 109, which is square in cross-section, extends through a square opening in the center of the disk 61 and is provided with a head 110 engaging the rear face of the disk. The stud 109 projects beyond 60 the casing 48 and receives a wing nut 111 provided with a squared recess 112, for imparting rotation to the disk. A small wing nut 113 passes through the wing nut 111 and is provided with a threaded shank 114 which engages in a suitably threaded opening axially arranged in the stud 109, for locking the wing nut and disk by friction in adjusted position.

In this modification the lock for retaining the base sections in adjusted position is as best shown 70 in Figure 16 a pivoted pawl carried by each of

the plates 17 and 18, this pawl being designated 115 and carried by the plate 18. The pawl is adapted to engage in one of a series of openings 116 formed in an upstanding flange 117 formed on one end of the bottom plate 13. A spring 118 maintains the pawl normally in the engaging position and the free end of this pawl is provided with a finger portion for facilitating its disengagement as desired.

It will be observed from an inspection of Figure 8 that, if desired, the tubular members 59' shown in Figure 20 may be employed for connecting the opposed sheet-engaging fingers 58, 59 and 57a of Figure 8. It is to be understood that where the connecting tubular members 59' are not employed in Figure 8, then the mechanism for shifting the parts of the sheet-engaging fingers may be duplicated at the right side of Figure 8, as shown at 111a.

It is further to be understood that, while this duplication may be resorted to, the sets of fingers 59 at the right of Figure 8 may be shifted by grasping the fingers themselves, if desired, and dispensing with duplicating the shifting disc and associated mechanism previously described.

Referring now more particularly to the alternative forms of the invention shown in Figures 17, 18, 19 and 20, these alternative forms of the invention are provided for operating the opposed groups of pins on the hinge members 11 and 12 simultaneously for the purpose of locking and unlocking the sheets in the binder.

Referring first to Figures 17 to 19, I provide a bracket 79 riveted to the plate 15 and lying transversely thereof in a position substantially in the vertical plane passing through the planes of the pins of the opposed groups. This bracket 79 is provided at its upper end with a substantially cylindrical portion 80. This cylindrical portion 80 is formed by rolling the sheet-metal of the bracket 79 as shown in Figure 19.

The opposite ends of the cylindrical portion 80 may be split, as indicated at 80a, for facilitating the application and removal of the rocking member 81. The rocking member 81 is provided with curved jaws 82 which, due to inherent resiliency thereof, may be snapped over the member 80 in assembling the device, or the portion 82 may be slid on from one side or the other. However, it is desirable that the member 81 be resilient so as to facilitate removal of this member in the event that its use is not desired. In order to prevent longitudinal movement of the rocking member 81 on the bearing member 80, stop members 81a, 81a' may be inserted in the portions 82.

The rocking member 81 is provided with a cylindrical bearing portion 82a, and this portion is adapted to receive the reduced ends 84 of the pin members 83. Similar extension pin members 83a, provided with extension portions 84a, are inserted in the bottom bearing portion 82. Obviously, these bottom members 83 have no rocking movement, as they are the relatively stationary members of each pin group. Upon rocking pins of one group the motion thereof is imparted through the member 82a, and the removable pins of the group thus lock the unlocking sheets in the binder.

Another manner is shown in Fig. 20 for insuring the simultaneous operation of the groups 145 wherein the pins 58 and 59 are connected by a tubular member 59', these members performing the function similarly to the sleeve 82a previously described.

It will thus be seen from the foregoing that this 150

invention permits of the relative adjustment of the base for affording changeable dimensions, also permits the angular adjustment of a plurality of groups of sheet-engaging members relative to the base, also the changing of the contour of the sheet-engaging member for engaging and disengaging a sheet, and the locking of the device in its various adjustable positions.

Having thus described my invention and illustrated its use, what I claim as new and desire to secure by Letters Patent is:

1. A loose leaf binder including sheet-engaging elements having parts whereby they may be variable in contour, means for shifting the parts of said elements to change their contour to form relatively staggered abutments projecting in opposite directions for engagement with complementary recesses in a sheet to hold the same against displacement.

2. A loose leaf binder comprising two sections movable toward and away from each other, a set of sheet-engaging elements variable in contour on each of said sections and oppositely disposed so that when the binder is closed the respective ends of said sheet-engaging elements are in abutting relationship, means for shifting said elements to change their contour to form relatively staggered abutments projecting laterally in opposite directions for engagement with complementary recesses in a sheet to hold the same against displacement.

3. A loose leaf binder including a base of variable dimensions comprising sections movable toward and away from each other, a group of sheet-engaging pins on each of said sections, said groups being in opposed relationship, the individual sheet-engaging pins of said groups each including relatively angularly displaceable parts for changing the transverse contour thereof, said pins being adapted to engage sheets having complementary apertures therein, means for relatively displacing the complementary parts of one of said groups of pins to form a locking engagement with the sheets, and means for simultaneously relatively angularly displacing the parts of the pins of the complementary opposed group.

4. A loose leaf binder including a base of variable dimensions comprising an intermediate section and end sections movable toward and away from each other, a group of sheet-engaging pins on each of said end sections, said groups being in opposed relationship, the individual sheet-engaging pins of said groups each including relatively angularly displaceable parts for changing the transverse contour thereof, said pins being adapted to engage sheets having complementary apertures therein, means for relatively displacing the complementary parts of one of said groups of pins to form a locking engagement with the sheets, and means on said intermediate section for simultaneously relatively angularly displacing the parts of the pins of the complementary opposed group.

5. A loose leaf binder including a group of sheet-engaging pins, each pin including complementary parallel parts, means for simultaneously moving one of the parts of each of said pins transversely of the axis thereof comprising a bar on which certain of said parts are carried, and a disk member rotatable for imparting motion to said bar.

6. A loose leaf binder including a group of sheet-engaging pins, each pin including complementary parallel parts, means for simultaneously moving one of the parts of each of said pins transversely of the axis thereof comprising a bar on

which certain of said parts are carried, and a rack bar member and a pinion engaging therewith for imparting reciprocation to said pin-carrying bar for displacing the pin parts carried thereby.

7. In a loose leaf binder, pairs of opposed sheet-engaging elements comprising each relatively displaceable parts for changing the external contour of the sheet-engaging elements, sliding bars for imparting relative movement to said parts of said sheet-engaging elements, means for simultaneously actuating said bars comprising a floating block mounted between said groups, relatively movable straps slidably mounted in said block and having universal joint connections in the outer ends thereof, and means connected to said universal joints for imparting displacement to said pin-carrying bars.

8. In a loose leaf binder, a base member of variable dimensions having portions movable toward and away from each other, pairs of opposed sheet-engaging elements comprising each relatively displaceable parts for changing the external contour of the sheet-engaging elements, sliding bars for imparting relative movement to said parts of said sheet-engaging elements, means for simultaneously actuating said bars comprising a floating block mounted between said groups, relatively movable straps slidably mounted in said block and having universal joint connection in the outer ends thereof, and means connected to said universal joints for imparting displacement to said pin-carrying bars, said block and straps automatically accommodating themselves in length to the displacement of the parts of said base member.

9. In a loose sheet holder, a base having sections displaceable relatively for varying the dimensions thereof, sheet engaging pins on said sections arranged in opposed groups, means for relatively angularly displacing said groups of sheet-engaging pins, and means for fixing the adjustment of such angular displacement of said pins so that the adjacent ends thereof may be positioned to permit of insertion and removal, or transfer therebetween, of sheets to be held thereby.

10. In a loose sheet holder, a base having sections displaceable relatively for varying the dimensions thereof, sheet-engaging pins on said sections arranged in opposed groups, means for relatively angularly displacing said groups of sheet-engaging pins independently of displacement of said sections, and means for maintaining such degree of displacement of said pins so that the adjacent ends thereof may be positioned to permit of insertion and removal, or transfer therebetween, of sheets to be held thereby.

11. In a loose sheet holder, a base having sections relatively displaceable for varying the dimensions thereof, housing portions hingedly mounted on said sections for angular displacement relatively thereto, groups of sheet-engaging pins carried by said housings in opposed relationship, means connecting said sections and housings and arranged to maintain angular adjustment of the latter for maintaining said groups of pins when desired in positions of angular relationship.

12. In a loose sheet holder, a base having sections relatively displaceable for varying the dimensions thereof, housing portions hingedly mounted on said sections for angular displacement relatively thereto, groups of sheet-engaging pins carried by said housings in opposed relationship, means including parallel plates connecting

said sections and housings, locking screws passing through said plates to maintain angular adjustment of the latter for maintaining said groups of pins when desired in positions of angular relationship.

13. In a loose sheet holder, a base including a displaceable section for varying the dimensions of said base, sheet-engaging elements on said section variable in contour, means on said section for shifting said elements to change their contour to form relatively staggered abutments projecting in opposite directions for engaging with complementary recesses in a sheet to hold the same against displacement, and means for angularly displacing and adjusting said sheet-engaging elements.

14. In a loose sheet holder a base having sec-

tions relatively displaceable for varying the dimensions thereof, housing portions hingedly mounted on said sections for angular displacement relatively thereto, groups of sheet-engaging pins carried by said housings in opposed relationship, means in said housings for shifting the parts of said sheet-engaging pins for changing their contour to form relatively staggered abutments projecting in opposite directions for engagement with complementary recesses in a sheet to hold the same against displacement, means connecting said sections and housings and forming locking means for maintaining angular adjustment of the housings for holding the groups of pins in distorted positions of angular relationship.
